UNITED STATES PATENT OFFICE.

JONAS NORTHRUP, OF HOPEDALE, MASSACHUSETTS, ASSIGNOR TO DRAPER COMPANY,
OF HOPEDALE, MASSACHUSETTS, A CORPORATION OF MAINE.

THREAD-PARTER FOR LOOMS.

1,078,210.

Specification of Letters Patent. Patented Nov. 11, 1913.

Application filed September 9, 1911. Serial No. 648,539.

To all whom it may concern:

Be it known that I, JONAS NORTHRUP, a citizen of the United States, residing at Hopedale, in the county of Worcester and State of Massachusetts, have invented an Improvement in Thread-Parters for Looms, of which the following description, in connection with the accompanying drawings, is a specification, like letters on the drawings

10 representing like parts.

The invention to be hereinafter described relates to that class of looms in which replenishment of the filling is automatically effected when necessary, and more particularly to the means employed for parting the filling ends at the changed side of the loom.

In devices of this general character it is desirable that the filling ends, that would otherwise extend from the cloth selvage due 20 to change of filling, be trimmed off evenly and close to the selvage. On the one hand, due regard must be had to the desirability of parting the filling end closely adjacent the cloth selvage, and, on the other hand, 25 that the means employed be of a character that will not cut or injuriously act upon either the cloth or its selvage.

With these general considerations in view, the aims and purposes of the present invention are to provide a parting device for the filling ends that will be simple in construction and yet will act effectively to part the filling ends close to the cloth selvage without liability of injuring either the cloth or 30 selvage, all of which will more clearly appear from the following description and accompanying drawings of one form of means for carrying the invention into practical effect.

40 In the drawings: Figure 1 shows the present invention in side elevation and part of the lay as it moves forward under the usual lay actuating means; Fig. 2 is a front view of the parts shown in Fig. 1, the lay being omitted; Fig. 3 is a section on the line 3—3, Fig. 2; and Fig. 4 is a detail partly in section showing the means for holding the elements of the parting device in normal position.

45 In order that the filling ends or threads be uniformly parted closely adjacent the cloth selvage without liability of injuring the cloth, the present invention contemplates the association of means, such as a temple, to 50 securely hold the cloth adjacent the selvage

and a parting device, preferably formed as a blade or blades, the construction being such that during the action of the parting device the cloth shall be securely held at the selvage to insure proper action of the parting device, and that thereafter the cloth may be released to enable the usual forward movement thereof as the weaving proceeds.

The present embodiment of the invention 65 shows a jaw temple having the lower jaw 1, and the upper jaw 2 between which the cloth passes. The upper jaw 2 is hung from a stud shaft 3 by means of the sleeve 4 and link 5, which is pivotally connected to the 70 upper jaw 2 by means of the lugs 6, 6 and pin 7. Projecting from the sleeve 4 is an arm 8, Fig. 1, on which acts a spring 9 normally tending to turn the sleeve in a direction to close the upper movable jaw 2 upon the lower fixed jaw 1. Mounted on the arm 8 is a rocking member 10, preferably pivoted to the arm 8 at 11, Fig. 1, although it may be otherwise formed. Pivotally mounted on the temple body at 12 75 is a wiper, which, just as the lay reaches its extreme forward position in its beat-up movement, wipes under the member 10 to raise and then release the arm 8 and thereby 80 separate the two jaws to temporarily release the cloth and then reclamp it. This wiper in the form of the invention shown 85 comprises a member 13 having a roller 14 to engage and disengage the rocking member 10, and a tail piece 15 adapted to be 90 engaged by the lay as it reaches its forward position or just prior thereto.

A spring 16 disposed between the lug 17 on the wiper and a lug 18 on the temple body serves to hold the wiper in normal 95 position, as indicated in Fig. 1, ready to be actuated by the lay for operating the jaws in the manner already described.

The lay or lay beam 19 may be carried by the usual lay swords and be actuated 100 in any usual manner, which being well understood by those skilled in the art needs no further description. In order to actuate the wiper the lay 19 may have a bunter 21, adjustable as by screw thread connection 105 with the lay, as shown.

The jaw temple and its operating parts may be as fully shown and described in my prior Patent No. 956,725, dated May 3, 1910, and to said patent reference may be had for 110

more full and detail description of the construction and operation of the jaw temple whereby it is enabled to hold the cloth during the beat up movement of the lay and 5 then during the terminal portion of such beat up movement temporarily unclamp and then clamp the cloth.

Seated in a recess of the temple head and adjacent the outer end portions of the fixed 10 and movable jaws of the temple is the stationary or fixed member 22 of the thread parter with which co-acts the rocking member 23 of the thread parter. The parting edge of the fixed member of the parter as 15 well as the edge 24 of the rocking member may be formed as cutting edges, but this may obviously be otherwise if desired.

The rocking member 23 is mounted on and fixed to the rock shaft 25 which extends 20 through a suitable bearing 26 in the temple head and has secured to its exterior portion, as by the pin 28, an actuating arm 27, Figs. 2 and 4. The fixed member 22 of the thread parter is seated in a holding recess 29, 25 Figs. 2 and 3, of the temple head and is penetrated by the rock shaft 25 which actuates the rocking member of the thread parter, and also serves to maintain the fixed member seated in its holding recess.

30 The upper end portion of the rocking arm 27 is provided with a head having a recess 30 in which and a recess 31 of the temple head, Fig. 4, is seated the spring 32, one end of which is secured to the head of the actuating arm at 33 and the other end of which is secured at 34 to the temple head, the construction and arrangement being such that the spring 32 acts torsionally to maintain the rocking member 23 of the thread parter 40 in open position, as indicated by Fig. 3, to receive between it and the fixed member the filling end to be parted and in addition it acts expansively to force the rocking member of the parter transversely and against 45 the fixed member of the parter, whereby the two members are always maintained in proper co-acting relation to sever or part the filling between them. The expansive character of the spring 32 likewise acts to 50 maintain the fixed member of the thread parter in its holding recess.

As hereinbefore pointed out, it is desirable that the thread parter shall act to part the filling end at the selvage while the cloth 55 is firmly clamped between the jaws of the temple, and as one means to this end the temple jaw opening means and the actuating arm for the parter are so related that as the lay beats up it will first act upon the actuating arm of the parter to part the filling while the jaws of the temple hold and clamp the cloth in position, and thereafter as the lay continues its beat up movement, and subsequent to parting the filling end, it 60 will cause the jaws of the temple to release

and then reclamp the cloth as hereinbefore fully described. As one means for operating the parter, the lay 19 has an adjustable bunter 35, substantially as shown diagrammatically in Fig. 1.

From the construction described, it will be evident to those skilled in the art that the present invention provides a simple and efficient device whereby the cloth may be securely held during the action of the thread parting means and thereafter temporarily released to effect the usual take-up; and further that the unitary means, such as the spring 32, furnishes a compact, simple and protected device for normally holding the members not only in open position to receive the filling end between them, but also to maintain, even after considerable wear, the parting edges of the fixed and rocking members in proper co-acting relation. The torsional effect of the spring 32 secures the first of these effects and its expansive quality the other, a stop 36, Figs. 2 and 4, serving to limit the torsional action of the spring and consequently the position of the parting members when in normal position. It will be noted also that while the cloth remains clamped and in fixed position between the jaws of the temple, the action of the thread parter severs the filling end close to the selvage with precision and uniformity, and as contributing to this end that the thread parter is mounted on the fixed jaw or stationary part of the jaw temple.

What is claimed is:

1. In a loom, the combination of a jaw temple and a thread parter, means for opening and closing the jaws of the temple for releasing and clamping the cloth, means for causing the thread parter to part the thread adjacent the selvage of the cloth while the jaws of the temple are clamped upon the cloth, and means for adjusting the time of action of said cutter more or less in advance of the jaw releasing movement.

2. In a loom, the combination of a jaw temple, means for opening the jaws of the temple as the lay moves forward and permitting them to close again prior to backward movement of the lay, a thread parter, and means for actuating the thread parter to sever a thread end adjacent the cloth selvage while the temple jaws are closed upon and hold the fabric stationary.

3. In a loom, the combination of a jaw temple and a thread parter mounted adjacent one edge of the temple, means for opening and closing the jaws of the temple for releasing and clamping the cloth, and means for actuating the thread parter to part the thread adjacent the selvage of the cloth while the jaws of the temple are clamped upon and hold the cloth.

4. In a loom, the combination of a jaw temple, means for opening and closing the

jaws of the temple for releasing and clamping the cloth, a thread parter carried by one of the jaws of the temple adjacent the edge thereof, and means for actuating the thread parter to part a thread adjacent the cloth selvage prior to the releasing movement of the jaws and while the jaws of the temple hold the fabric in fixed position.

5. In a loom, the combination of a jaw temple, a thread parter carried thereby and comprising two members, means acting normally to hold said members in thread engaging position and maintain their parting edges in lateral coöperating relation, and
10 means acting upon the jaw temple to cause the jaws to clamp and hold the fabric from which the thread projects during the action of the thread parter.

6. In a loom, a jaw temple, a thread parter 20 mounted on said temple adjacent one end of the temple jaws, said thread parter comprising a fixed and a rocking member, an actuating arm for rocking the rocking member, a spring acting normally to maintain said 25 members in open position to receive a filling end and for holding them laterally in co-operating relation and means for causing the jaws of the temple to clamp and hold the fabric between them during the action of 30 the thread parter.

7. In a loom, a jaw temple, a thread parter mounted on said temple adjacent one end of the temple jaws, said thread parter comprising a fixed and a rocking member, an actuating arm for rocking the rocking member 35 having a recessed head, a spring seated in the recess of said head and acting to maintain the fixed and rocking members of the thread parter normally in open relation and to force them laterally into co-acting relation and means for holding the jaws of the temple closed upon the fabric from which the thread projects during the action of the thread parter.

8. In a loom, the combination of a jaw 40 temple having a fixed and a movable jaw, a thread parter mounted on the fixed jaw of the temple, and means for operating the thread parter while the cloth is clamped between and held by the jaws of the temple 45 and for thereafter separating said jaws to release the cloth.

In testimony whereof, I have signed my name to this specification, in the presence of two subscribing witnesses.

JONAS NORTHROP.
